LIQUID PUMP

Louis V. Altman and Henry Jung, Racine, Wis., assignors to Applied Engineering of Wisconsin, Racine, Wis., a corporation of Wisconsin

Application July 2, 1954, Serial No. 440,888

8 Claims. (Cl. 222—324)

This invention relates to pumps, and, more particularly, it relates to pumps of the type mountable on oil containers such as the pint and quart size oil cans.

It is an object of this invention to provide an oil can pump which attaches directly to an oil can and is inexpensive but efficient and durable. This object is best achieved through the utilization of metal stampings which form parts of the pump.

Another object of this invention is to provide an oil can pump which attaches directly to an oil can and is stabilized thereon by the can itself. In achieving this object, the pump and can are unified to permit them to be manipulated for at least most oiling operations.

Still another object is to provide a single size oil can pump which can be attached to different sizes of oil cans, and be securely affixed thereto, and be capable of pumping all of the oil from either a pint or a quart or a like size of can, without the need of any changes in the pump structure.

Another object is to provide an improved liquid pump.

Other objects and advantages will become apparent upon reading the following description in conjunction with the accompanying drawings, wherein:

Fig. 1 is a side perspective view of a preferred embodiment of this invention.

Fig. 2 is a fragmentary side elevational view of the embodiment shown in Fig. 1 but with the operating parts in a different position.

Fig. 3 is a sectional view taken on the line 3—3 of Fig. 2.

Fig. 4 is a sectional view taken on the line 4—4 of Fig. 2.

Fig. 5 is a sectional view taken on the line 5—5 of Fig. 2.

Similar reference numerals refer to similar parts throughout the several views.

Fig. 1 shows a preferred embodiment of a pump 10 of this invention mounted on a quart size oil can 11. To facilitate a description of the pump 10, parts of the assembly are broken away to reveal internal parts. The pump 10 preferably consists of a vertically disposed inverted cup-shaped member 12 which includes a connector 13 shown to be a lower threaded section which is for a purpose described later. Telescopically associated with the member 12 is a tube or pump housing 14 which contains the operating parts of the pump as shown in Figs. 2 and 3. The preferred manner of securing the housing 14 to the member 12 is described later. Fig. 1 further shows a member 16 attached to an intermediate section of the member 12 to extend transversely thereto in a mounting portion 17 which is connected to a handle 18. As shown, it is preferred that the portion 17 be flat and circular with integral diametrically opposite extensions 19 and 20. Also, the end of the handle 18 terminates in a can punch 22.

With the foregoing described structure, it should be understood that before the pump 10 is mounted onto the can 11, the punch 22 is used to form a hole in the cen-

2

ter of the top 23 of the can. Then the housing 14 is inserted into the hole which is substantially concentric with the can top. The pump threads 13 are self-tapping threads which are tapered down at their bottom end diameter to enable them to readily screw onto the can top to mount the pump onto the can in the position shown. It should also be appreciated that the bottom surfaces of the mounting extensions 19 and 20 abut the top of the can rim 24, and, as the threads 13 screw onto the can top, the latter is pulled up to the top level of the rim 24 to abut the bottom of the pump mounting portion 17.

In this manner, the pump 10 is stabilized onto the can 11 by utilizing the can rim to obtain a support point on each opposite side of the attachment point of the threads.

Further shown in Fig. 1 is a fulcrum 26 which is preferably spot welded to the top horizontal surface of the mounting extension 19. The fulcrum is angled to extend vertically above the extension 19 to terminate in a reduced tip 27. Also, as shown in Figs. 1, 2, and 5, a shoulder portion 28 exists on the fulcrum, immediately below the tip 27. A preferably S-curved trigger 31 is provided at its mid-portion with a circular hole 32 which receives the fulcrum tip 27 while an end of the trigger contains a second hole 33 which engages a vertical connecting rod 34 projecting above the pump member 12. The latter engagement is at a point below an acorn nut 36 threaded onto the upper end of the rod 34 with the nut larger than the hole 33 to secure the assembly. With this arrangement, depressing the trigger 31, from the position shown in Fig. 1 to that shown in Fig. 2, will cause the connecting rod to be raised to extend further above the member 12. In this operation a liquid pumping stroke is, of course, effected and it should be understood that the trigger 31 has pivoted about the fulcrum tip 27 on the shoulder 28. In so doing, the hole 33 slides with respect to the rod 34 to compensate for the arcuate movement of the hole and the straight vertical axial movement of the rod 34. Since the latter, therefore, can move axially with respect to the pump 10, the problem of fluid sealing the rod with the pump is simplified.

To complete the description of the pump parts shown in Fig. 1, it is noted that a liquid outlet spout 37 is threaded into the member 12 to extend transversely thereto on the side opposite the handle 18. Also, an axially movable and telescopically arranged depth compensator 38 is located in the bottom end of the housing 14. The compensator 38 is best shown in Figs. 2 and 3 wherein it is seen that a tube 39 is threaded at the top to attach to a bored piston 41. The lower end of the tube contains a side slot 42 which communicates the exterior of the compensator with the interior of the tube. Also, to secure the compensator to the housing 14, it is preferred to crimp the bottom end of the housing to provide an edge 43 which is smaller in diameter than the diameter of the piston 41. The latter can then slide axially within the housing but it can not slide out of the housing 14.

As shown in Fig. 2, a pint size liquid can 44 is employed to mount the pump 10. In this case, the compensator 38 has moved up in the housing 14 from the position of Fig. 1 to that of Fig. 2 to accommodate the different lengths of the cans 11 and 44. The compensator piston 41 is substantially fluid tight with the inner wall of the tube 14, but it is free to slide therewithin. It slides downwardly under its own weight and upwardly by abutting the bottom of a can.

The pump mechanism is shown in Figs. 2 and 3 to be preferably of the type containing a piston or plunger 46 snugly fitted into the tube 14 to be slideable therewithin. The piston is hollow with an opening 47 in the bottom thereof to seat a ball valve 48. The top end of the piston receives a transverse pin 49 anchored in the piston with

a center portion passing through a lower eye end 51 of the connecting rod 34. Also, Fig. 3 shows the rod 34 passes through an upper hole 50 in the member 12 to extend between the piston 46 and the trigger 31.

Thus, the rod 34 reciprocates the piston to pump liquid from the tube 14 and out the spout 37 in the piston upward movement as the ball 48 then automatically closes the opening 47. The downward movement of the piston allows liquid to pass up into the tube 14 through the compensator 38. To automatically effect this downward movement, a coil spring 52 is disposed around the rod 34 and between the pin 49 and a fluid seal washer 53 at the top of the member 12. The washer, of course, has a central opening through which the rod 34 can pass.

Fig. 4 shows the preferred manner of attaching the spout 37 to the members 12 and 14 by threading thereinto. The spout is, of course, then in fluid communication with the inside of the tube 14. With this arrangement, the tube 14, member 12, and the spout 37 are all secured together. The washer 53 is above the spout 37, as shown in Fig. 2.

Thus, it will be seen that a simple but durable liquid pump is disclosed. The pump is inexpensive in that certain parts, such as the mounting portion 16, with the extensions 19 and 20, the handle 18, the fulcrum 26, and the trigger 31 are all readily made by stamping. Even the punch 22 is stamped from the same metal which forms the handle 18. Further, the assembly is simple in that the tube 14 and the member 12 and the compensator 38 are all telescoped together with the first two members being secured together by the spout 37.

In the mounting of the pump onto the can, the foregoing describes the pump transverse extension members 19 and 20 at the upper end of the pump with said members engaging the top rim of the can. Obviously, if the extension member 20 were not there, then the lower edge of the spout 37 would serve as the support point at the adjacent rim of the can. Further, if it is preferred, the spout could be moved down to the level where the extension 20 is now shown. Thus, while a specific embodiment of this invention has been shown and described, the scope thereof should be limited only by the appended claims.

We claim:

1. A liquid pump comprising a tubular pump housing having a liquid inlet at one end thereof and a liquid outlet at the side of the other end thereof with an intermediate liquid chamber, a pump piston disposed within said chamber, a hollow cylindrical member of a diameter to snugly telescope with the end of said housing containing said outlet, said cylindrical member extending beyond said housing end with a reduced opening in the extending portion and having a liquid outlet aligned with said housing outlet, a piston operating rod projecting through said reduced opening to connect to said pump piston, a liquid spout threaded into the aligned outlets of said housing and said cylindrical member to secure said pump assembled.

2. A can mountable liquid pump comprising an upright tubular pump housing having a liquid inlet at the lower end thereof and a liquid outlet at the side of the upper end thereof with an intermediate liquid chamber, a plunger snugly disposed within said chamber to reciprocate therewithin, a hollow cylindrical member of a diameter to snugly telescope with the upper end of said housing, said member forming an extension to said housing and having a reduced axial opening in said extension and having a liquid outlet aligned with said housing outlet, a plunger operating rod received within said reduced axial opening to connect at one end to said plunger, a liquid spout threaded into the aligned outlets of said housing and said cylindrical member to secure the latter two parts, exterior threads formed on the assembly of the latter two parts immediately below said spout to permit threadedly attaching said pump onto the top of said can.

3. A can mountable liquid pump comprising a tubular

pump housing having a liquid inlet and a liquid outlet with an intermediate chamber, a pump plunger disposed within said chamber to be reciprocable therewithin, a hollow cylindrical member of a diameter larger than said housing diameter to snugly telescope therearound and having a liquid outlet aligned with said housing outlet, a spout threaded into said housing and said cylindrical member aligned outlets, a handle attached to said cylindrical member to extend therefrom on substantially the same plane with said spout, a threaded section on the telescoped portion of said cylindrical member immediately below said spout and said handle whereby said threaded section screws into a hole in the top of said can to mount said pump onto said can.

4. A liquid pump for mounting onto a cylindrically shaped liquid can of the type having a can top and having a circular rim around the circumference of said can top with said rim extended beyond the surface of said can top, the combination comprising a pump housing having a lower liquid inlet and an upper liquid outlet, a threaded connector on said housing intermediate said inlet and said outlet for threading into said can top, a liquid plunger disposed in said housing for pumping liquid therethrough upon reciprocation of said plunger in said housing, a spout attached to said housing to communicate with said liquid outlet, a handle attached to said housing above the threads of said connector and extending from said housing in opposite directions and in dimensions at least equal to the radius of said can for overlying and abutting said rim of said can when said pump is centrally mounted on said can top by said connector being threaded into said can top.

5. A can mountable liquid pump comprising a housing having a liquid inlet at one end and a liquid outlet at the opposite end, a spout attached to said housing and in communication with said liquid outlet, a threaded connector on said housing immediately below said spout for threading into a hole in the top of said can, a handle attached to said housing above the threads on said connector and extending in opposite directions from said housing for abutting opposite sides of the top edge of said can when said pump is mounted on said container, a plunger disposed in said housing for moving liquid therethrough to said liquid outlet, a connecting rod attached to said plunger and projecting from said housing, a fulcrum mounted on said handle, a lever pivoted on said fulcrum and attached to said connecting rod for reciprocating the latter.

6. A can mountable liquid pump comprising a tubular pump housing for use in an upright position and having a liquid inlet at the lower end thereof and a liquid outlet at the upper end thereof and having an intermediate liquid chamber, a pump plunger snugly disposed within said chamber to be reciprocable therein, a connector attached to the upper end of said housing and having a liquid outlet in liquid flow communication with said liquid outlet of said housing, a spout attached to said connector and in liquid flow communication with said liquid outlet of said connector, said connector including a threaded portion disposed below said spout, transversely extending members attached to said connector and projecting on opposite sides thereof in a plane intermediate said spout and said threaded portion for abutting diametrically opposite locations on the rim of the top of said can when said threaded portion is threaded into an opening in said top of said can, a handle rigidly connected to one of said transversely extending members, means on said one of said transversely extending members and connected to said pump plunger for reciprocating the latter.

7. A liquid pump comprising a pump housing for use in an upright position and having a liquid inlet at the lower end thereof and a liquid outlet at the upper end thereof and having an intermediate liquid chamber, a plunger disposed in said chamber to be reciprocable

therein, a rod attached to said plunger and projecting above said housing for movement axially of said housing, a nut threaded on the upper end of said rod, a pump handle attached to said housing and projecting transversely therefrom, a fulcrum mounted on said handle and extending thereabove with the upper end of said fulcrum reduced in size to present a shoulder and angularly disposed away from said housing, a lever having a central opening intermediate of the length of said lever and an end opening on one end of said lever with said central opening snugly receiving said upper end of said fulcrum and said end opening loosely receiving said rod below said nut all for pivotal movement of said lever on said shoulder of said fulcrum to reciprocate said rod and said plunger.

8. A liquid pump comprising a pump housing for use in an upright position and having a liquid inlet at the lower end thereof and a liquid outlet at the upper end thereof and having an intermediate liquid chamber, a pump plunger disposed within said chamber to be reciprocable therein, a spring in said housing for yieldingly urging said plunger downwardly, a plunger rod attached to said plunger and extending therefrom through said upper end of said housing for reciprocation along the axis of said rod, an enlarged portion on the upper end of said rod, a mounting member attached to said housing and extending transversely thereto, a fulcrum attached to said mounting member and projecting thereabove and terminating at the upper end of said fulcrum

with a reduced portion disposed above the lower end of said enlarged portion on said rod when the latter with said plunger are in the extreme downward position under the influence of said spring, said reduced portion disposed angularly away from said housing and having a shoulder below said reduced portion, a lever pivotally supported on said shoulder of said fulcrum and having a central opening receiving said reduced portion and said lever having an end opening receiving said rod below said enlarged portion, said reduced portion of said fulcrum being sufficiently curved and spaced from said rod with respect to the spacing between said central opening and said end opening on said lever a distance sufficient to secure said lever on said reduced portion of said fulcrum when said plunger and said rod are in said downward position.
